UNITED STATES PATENT OFFICE.

WILLIAM W. BEACH, OF BROOKLYN, ASSIGNOR TO THE STANDARD OIL COMPANY, OF NEW YORK, N. Y.

BARREL-CLEANING MACHINE.

SPECIFICATION forming part of Letters Patent No. 293,843, dated February 19, 1884.

Application filed August 13, 1883. (No model.)

To all whom it may concern:

Be it known that I, WILLIAM W. BEACH, of the city of Brooklyn, in the county of Kings and State of New York, have invented an Improved Barrel-Cleaning Machine; and I hereby declare the following to be a full, clear, and exact description thereof, reference being had to the accompanying drawings, which form a part of this specification.

10 This invention relates to improvements in apparatus for cleaning and renovating barrels that have been used and preparing them for further use. It is more especially intended to be used for cleaning oil-barrels which have 15 been returned to be again filled after having been used in transporting oil; but it is also applicable for cleaning other kinds of barrels.

Hitherto, when barrels in which oil has been transported have been returned to be again 20 filled, it has been usual to clean them by hand, which is a laborious and tedious process; but by means of my invention such barrels can be cleaned very rapidly by steam-power or other suitable power, and at comparatively a very 25 trifling expense. In my improved machine the barrel to be cleaned is clamped between two revolving chucks or heads of novel construction, which are driven by steam-power or other suitable power, and a brush or sweeper shaped 30 to conform to the contour of the barrel is brought in contact therewith while it is being rotated between said chucks. A brush is also simultaneously brought into contact with each head of the barrel for the purpose of cleaning 35 them, and provision is made for saturating the last-mentioned brushes with naphtha or similar liquid, to remove the lettering and other marks that may have been placed thereon. By these means three or four revolutions of the 40 barrel in contact with said brushes are generally sufficient to thoroughly clean all parts of the exterior surface of a barrel.

The invention consists, first, in a barrel-cleaning machine having two revolving chucks 45 or heads, between which the barrel is clamped, one of which is arranged to be oscillated horizontally, and a brush formed to correspond to the contour of the barrel, together with appliances, hereinafter particularly described, for bringing said brush into and out of contact with the barrel and for operating said clamp-

ing-chucks; secondly, in the combination, with said chucks and brush, of two other brushes for simultaneously cleaning the heads of the barrel, said brushes being provided with appliances for keeping them in contact with the heads while the barrel is being rotated; and it further consists in certain novel constructions and combinations of parts, all of which are hereinafter particularly set forth.

In the accompanying drawings, Figure 1 represents a side elevation of my improved machine. Fig. 2 is an elevation of one end of the same. Figs. 3, 4, and 5 are details hereinafter referred to and explained.

Similar letters of reference indicate the same parts in all the several figures.

A is the frame of the machine, which may be of any suitable form and dimensions for holding the working parts.

B B' are two chucks or heads, which are fixed upon the ends of the shafts C C', respectively.

D D' are a fast and loose pulley fixed upon the shaft C, and driven by any suitable power 75 through the medium of a belt, a. The barrel to be cleaned is clamped between the chucks B B', as shown in Fig. 1.

E is a brush or sweeper suspended over the barrel by a rod, b, which latter is pivoted at 80 the end of a lever, F, that is fulcrumed on a post, c, on the top of the frame, and the free end of which extends beyond the end of the frame, as shown. The face of the brush E is curved to adapt it to the contour of the barrel, and said brush is raised by depressing the lever F, and whenever said lever is released the brush is brought evenly into contact with the barrel by the force of two coiled springs, f f', which are fitted between two pairs of bars, h h' and h' h', upon the guide-rods g g', the lower ends of which are attached to the two ends of the block d, to which the brush is secured. A cord or chain, H, is attached to the outer end of the lever F, and passed over pulleys (not 95 shown in the drawings) which are fixed in any convenient position above the machine, and to the other end of said cord H a weight, I, is attached, so that by the conjoint action of said weight and said springs f f' the brush is pressed 100 firmly and evenly against the sides of the barrel. Another cord, H', is also attached to the

free end of the lever F, and suspended therefrom, to the lower end of which a ring J, is attached, which, when the brush is to be held out of contact with the barrel, is passed over the 5 end of a rod, K, secured to the frame of the machine.

L is a lever pivoted at one end on a bracket, l, secured to the frame, the free end of which extends over and in contact with the rod K, so 10 that whenever the end of the lever is pushed outward (in the direction of the arrow in Fig. 4) it pushes the ring J off the rod K, and thereby the lever F is released and the brush E brought into contact with the barrel by means 15 of the weight I and springs f f'. Ordinarily I make the bristles of the brush E from wire, and in order to avoid the production of sparks by the friction, I use brass wire for the purpose. About No. 15 gage is the proper size 20 of wire.

The rims m m of the chucks B B' are provided with beveled grooves, as shown in Figs. 3 and 5, to receive the ends of the barrel, which fit thereinto; and the radial arms n 25 n, which connect said rims with the hubs p p, are set at an angle, so that said chucks are made concave or dished for the purpose of receiving the brushes N N', which are pressed against the heads of the barrel for the purpose 30 of cleaning the same while the barrel is being rotated. The shafts C C' are hollow, and the shafts P P', to which the brushes N N' are attached, are passed through them. Coiled springs o o are fitted on the shafts P P', between 35 the backs of the brushes and the hubs p p', for the purpose of pressing said brushes against the heads of the barrel, and a longitudinal groove, r, is cut in each, into which is fitted a pin, s, to prevent the shafts P P' from 40 turning. The brushes N N' may be made of hair or other suitable material, and for the purpose of removing the lettering or other marks that may be painted upon the heads of the barrel, said brushes may be saturated with 45 naphtha or other similar liquid. For this purpose the shafts P P' are made hollow or tubular, and connect at one end with the brush and at the other with a tube, t, through which the liquid is supplied from a tank or receptacle located in any convenient position.

The chuck B' is arranged to move horizontally back and forth a short distance, for the purpose of clamping and releasing the barrels as they are successively passed into the 55 machine, by means of the following-described devices: R is a rack-bracket fitted to slide upon a bar, u, immediately above and parallel with the shaft C', which is operated by a toothed segment, W, pivoted to an arm, S, 60 secured to the frame, through the medium of a lever, T, which is attached at one end to the segment W, its other end being extended toward the end of the lever L, so that both of said levers can be operated by the same 65 person simultaneously. Fixed on one arm of said bracket is a pin, w, which enters a circumferential groove in a flange, x, secured at

the end of the shaft C', so that whenever said bracket is moved back and forth a corresponding movement is imparted to the chuck 70 B'. These devices are most plainly shown in Fig. 5, which is an elevation on an enlarged scale.

The operation is as follows: The barrels are rolled along an inclined tramway, Y, passing through the machine, and are lifted from the rails by two pairs of inclined bars, k k', onto which they pass, and are thereby brought to a level with the chucks. Supposing the ring J to be on the rod K, as shown, the belt 75 a to be on the loose pulley D, and the chuck B' drawn back to admit a barrel, and a barrel to be upon the bars k k', the attendant first draws forward the lever T, which clamps the barrel between the chucks. He then 80 draws forward the lever L, which pushes the ring J off the rod K, thereby bringing the brush E into contact with the barrel, and at the same time shifts the belt a onto the fast pulley D', the rod y', to which the belt-shifter 85 y is attached, being pivoted to the lever L at z, and operated thereby, as shown in Fig. 4. The chucks being now in motion, the barrel is rotated thereby in contact with the several brushes, and when cleaned the attendant 90 pushes back the lever L to shift the belt, then pushes back the lever T to withdraw the chuck B'. The barrel is then 95 pushed off the bars k k' and rolls down the incline away from the machine. The bars k k' are attached to the tramway Y, as shown in Figs. 1 and 2.

What I claim as my invention is—

1. In a barrel-cleaning machine, the combination of a brush, E, shaped to conform to the contour of a barrel, and suspended by a rod, b, connected with a lever, F, for raising said brush, a pair of rotating chucks, B B', each constructed, as described, to clamp the 110 barrel, the rack-bracket R, toothed segment W, and lever T, for operating said chucks, and the guide-rods g g' and springs f f', connected with said brush, for bringing the same in contact with the barrel, the whole constructed as described, for the purposes set forth.

2. In combination with the brush E and the chucks B and B', each constructed and operated as described, the brushes N and N', 120 fitted upon the shafts P and P' within the cavities of said chucks, and kept in contact with the heads of the barrel, as and for the purpose set forth.

3. In combination with the chucks B and B', the brush E, attached to the rod b, which is pivoted to the end of the lever F, the guide-rods g g' and springs f f', cords H and H', rod K, ring J, and weight I, as and for the purpose set forth.

4. The combination, with the chucks B B' and their shafts C C', each constructed as described, of the devices for rotating and stopping said chucks, said devices consisting of

the lever L, rod K, ring J, pulleys D D', and belt-shifter y, fixed upon the rod y' and operated by said lever L, all constructed as shown and described.

5. In combination with the chuck B' and and its shaft C', the latter provided with the grooved flange x, the rack-bracket R, provided

with pin w, the toothed segment W, and lever T, said rack-bracket being fitted to slide on the bar u, as and for the purpose set forth.
